US00D591280S

(12) **United States Design Patent**
Irvine et al.

(10) **Patent No.:** **US D591,280 S**
(45) **Date of Patent:** **** Apr. 28, 2009**

(54) **REAR COVER FOR A HANDSET**

(75) Inventors: **Lee Irvine**, Thursley (GB); **Damian Mycroft**, Warwick (GB); **Nicol Boyd**, Brookfield (GB)

(73) Assignee: **Nokia Corporation**, Espoo (FI)

(**) Term: **14 Years**

(21) Appl. No.: **29/298,918**

(22) Filed: **Dec. 14, 2007**

(30) **Foreign Application Priority Data**

Jun. 14, 2007 (FI) ..... 20070117 M

(51) **LOC (9) Cl.** **14-03**

(52) **U.S. Cl.** **D14/248**

(58) **Field of Classification Search** ..... D14/137, D14/138 AA, 138 AB, 138 AC, 138 AD, D14/138 C, 138 G, 138 R, 147-148, 156, D14/218, 247-248, 341-347, 390, 399, 455-456, D14/496, 172, 188, 191, 192, 194, 207, 209.1, D14/214, 219, 225; D16/208, 217, 218, D16/219; D21/329, 331, 333, 517; 348/14.01-14.02; 361/814; 379/433.01-433.13; 455/90.3, 455/556.1-556.2, 566, 575.1, 575.3, 575.4; D13/164, 168, 108; 439/165; 343/702; 345/167, 345/168, 169

(57) **CLAIM**

The ornamental design for a rear cover for a handset, as shown and described.

DESCRIPTION

FIG. 1 is a front view of a rear cover for a handset showing our new design; and,

FIG. 2 is a perspective view thereof.

The broken lines immediately adjacent to the shaded region represent the bounds of the claimed design. The broken lines showing the remainder of the handset are for illustrative purposes only and form no part of the claimed design.
